CALCULATING MACHINE

Anthony B. Machado, San Leandro, Calif., assignor to Friden Calculating Machine Co., Inc., a corporation of California

Application April 3, 1944, Serial No. 529,332

2 Claims. (Cl. 235—75)

This invention relates to calculating machines. The invention is disclosed herein as embodied in a calculating machine of the type disclosed to C. M. F. Friden No. 2,229,889 which issued January 28, 1941, and for a disclosure of a complete machine, reference is to be had to said patent. In machines of this type, the registration of values in the accumulator is effected by uni-directional cyclic drive of the actuating means and by selective control of a reversible transmission mechanism which determines whether the registration is positive or negative. The drive is controlled by a clutch of the pawl and ratchet type, which is under the control of plus and minus keys. These keys also control adjustment of the transmission mechanism.

In machines of the type referred to, a number of different means has been employed to prevent accidental or deliberate misoperation of the plus and minus keys to cause engagement of the clutch without maintaining the reversing gear engaged. This sometimes resulted from a quick, light touch on the plus or minus key. One means for preventing this misoperation which has been tried consists in the use of spring latches. Friden Patent 2,279,455 shows a spring latch 116 (Fig. 5) for latching a depressed key 101 or 102. This latch was used in conjunction with a latch means shown in Friden Patent 2,310,280, which comprised the latches 241, 245 (Fig. 6) which latched the slide 234 in either additive or subtractive adjustment. Another means which was employed consisted of a lock for the plus-minus gate which was set by rotation of an actuator shaft. This type is shown in Friden Patent 2,229,889 (Fig. 13), lever 466 being rocked by the cam 463 on the drive shaft to engage the tooth 469 in the serrations 475 to 477. Moody Patent 2,279,481 shows a pin 24 (Fig. 4) mounted on the plus-minus gate which cooperates with a notched disc 22 on an actuator shaft. These latter means which depend on independent timing of the setting of the gate and the operation of the actuator sometimes led to difficulty in that it was possible to quickly depress the plus or minus key and release the gate before the actuator shaft had time to start turning and lock it in position.

In accordance with applicant's invention, a different approach to the problem has been made in that the reversing means is positively locked by operation of the clutch itself so that if the clutch is engaged, the reversing gear is necessarily locked.

One object of the invention is to provide means

controlled by a cyclically-driven drive part for maintaining the transmission mechanism in its adjusted position throughout each cycle.

Another object of the invention is to effect the above result through the intermediary of the depressed operation key which is thereby locked down during the cycle.

A further object of the invention is to effect the above results in connection with a clutch control means which may be adjusted for single or plural cycle operation.

Other objects will appear after the following disclosure.

In the drawings:

Fig. 1 is a vertical longitudinal section through the machine showing one order of the keyboard, accumulator, and the actuating and reversing means therefor.

Fig. 2 is a vertical longitudinal section through the machine to show the plus and minus keys, the clutch and control therefor.

Fig. 3 is a plan view of the parts shown in Fig. 2 with the plus and minus keys in section.

Fig. 4 is a vertical longitudinal section through the machine showing the mechanism disclosed in Fig. 2 as it appears from the other side.

Fig. 5 is a detail view of the levers operated by the plus and minus keys.

Fig. 6 is a fragmentary section taken on the line 6—6 in Fig. 4.

Figs. 7 and 8 show the positions of the clutch control parts during operation with the clutch control adjusted for plural cycle operation.

Figs. 9 to 11 show the positions of the clutch control parts during a cycle when the clutch control is adjusted for single cycle operation.

Referring to Fig. 1, the values set in the keyboard 20 are entered into the accumulator 21 by means of the uni-directional cyclic-drive shaft 22 which drives the actuating mechanism 23. The sign of the registration is controlled by a reversible transmission mechanism 24 which is normally retained in the neutral position shown in Fig. 1 and comprises, in each order, a pair of bevel gears connected by a sleeve 25 slidable on the shaft 26 and a bevel gear 27 on the shaft 28 of the numeral wheel 29.

By shifting the sleeve 25 and its bevel gears forwardly or rearwardly on the shaft 26, one or the other of the bevel gears is engaged with the bevel gear 27 to thereby establish a driving connection from the actuator 23 to the accumulator 21 and to determine whether the registration shall be positive or negative. The means for shifting the reversing gear comprises a slide 30

which extends transversely of the machine to act as a common operator for all the reversing gears, there being a reversing gear in each order. The slide is supported at its ends in slots in the side frames, the slot in the right side frame 31 (Fig. 2) being shown at 32. A similar slot is provided in the left side frame (not shown). The slide 30 is thus confined to translatory movement in a direction parallel to the shafts 26. To move the slide 30 a pair of similar arms, one of which is shown at 33 (Fig. 2) are secured to a transversely extending shaft 34. The upper ends of these arms are operatively connected to the slide 30. As shown in Fig. 3, the arm 33 has a stud 35 engaging in a notch in the end of the slide 30. Therefore, oscillation of the shaft 34 results in movement of the slide 30 to adjust the reversing gear.

The reversing gear is normally held in its neutral position, shown in Fig. 1, by means of a centralizer 40 which comprises a pair of spring-pressed arms 41, 42 engaging a pin 43 in an arm 44 secured to the shaft 34.

The shaft 34 is rocked one way or the other from its neutral position upon depression of either the plus key 50 or the minus key 51 in order to adjust the reversing gear 24 in accordance with the sign of the key depressed to cause positive or negative registration in the accumulator. In Fig. 2 the plus key 50 is shown in its depressed position. The key has a pin 52 which, upon depression of the key, engages a cam face 53 on an arm 54 secured to a shaft 55 so that depression of the key 50 causes the shaft 55 to be rocked clockwise as shown in Fig. 2. The minus key 51 when depressed causes the shaft 55 to be rocked counterclockwise. This is effected by means of a pin 56 on the key which is adapted to engage a cam face 57 on the arm 54. The shaft 55 (Fig. 4) has an arm 58 secured thereto which is pivotally connected at 59 to a link 60. The rear end of the link 60 is pivotally connected by means of the stud 35 (Fig. 2) to the arm 33. By this means rocking of shaft 55 causes rocking of shaft 34 so that depression of the plus key 50, for example, results in rearward movement of the slide 30 to engage the reversing gear 24 for positive registration. It is to be noted that as long as either key 50 or key 51 is in depressed position, the slide 30 will be maintained either forwardly or rearwardly of its neutral position to hold the selected gear on the sleeve 25 in mesh with the bevel gear 27 and that upon return of a depressed key to raised position, the reversing gear will be restored to its neutral position by the centralizer 40.

Depression of either key 50 or 51 also causes engagement of the clutch 70 (Fig. 2) as will now be explained. The motor 71 (Fig. 1) is connected to a pinion 72 (Fig. 2) which, through an intermediate gear 73, drives a gear 74 which is connected to the ratchet wheel 75 of the clutch. The ratchet wheel 75 is rotatable on the driven shaft 76. The driven side of the clutch comprises a plate 77 (Fig. 4) connected to the shaft 76 and provided with a pawl 78 pivoted thereon at 79. The pawl 78 (Fig. 2) is spring urged into engagement with the ratchet wheel 75 and is restrained from engaging the ratchet wheel by a control lever 80 (Fig. 7) pivoted at 81 and having a nose 82 which engages the shoulder 83 on the pawl 78. Upon clockwise movement of the lever 80 from the position shown in Fig. 7 to the position shown in Fig. 8, the pawl 78 is released to engage the ratchet wheel 75 and thus establish a driving

connection with the shaft 76. The control lever 80 has a spring 84 (Fig. 4) which tends to rotate the lever clockwise to clutch disengaging position.

The means for operating the clutch control lever will now be described. The plus and minus keys 50 and 51 (Fig. 2) are provided with pins 85 and 86 which are normally positioned above the open ends of inclined slots 87, 88 in an arm 89 secured to a rock shaft 90. Adjacent the arm 89 (Figs. 3 and 5), a lever 91 is secured to the shaft 80. Depression of either key 50 or 51 will result in rocking the lever counterclockwise as shown in Fig. 4.

Depression of either key causes closing of a switch in the motor circuit. The lever 91 (Fig. 5) has a slot 92 in its lower end engaging a pin 93 on a lever 94 provided with a pin 95 for closing the contacts 96 (Fig. 4).

To operate the clutch control lever to cause engagement of the clutch upon depression of either key, the upper end of lever 91 has pivotally mounted thereon at 97 a pair of levers 98, 99 (Figs. 2 to 4). The lever 99 has a link 100 (Fig. 4) pivotally connected to the forward end thereof. The forward end of the link 100 has a slot 101 embracing a pin 102 on a control lever 103 pivotally mounted at 104. A spring 105 is provided to urge the link 100 forwardly which results in urging the lever 99 counterclockwise on its pivot 97 and also in urging the lever 91 clockwise. The control lever 103 can be adjusted to either an up or a down position for plural cycle or single cycle operations as will become evident.

The rear end of the lever 99 has a notch 106 (Fig. 7) formed therein which, in the up position of the control lever 103 shown in Fig. 7, embraces a pin 107 on the clutch control lever 80 so that upon depression of either the plus or the minus key, for example the plus key as shown in Fig. 8, the control lever 80 is rocked clockwise to release the pawl 78 to cause engagement of the clutch. This is the plural cycle position of the lever 103 in that as long as the key is held depressed, the lever 99 holds the clutch control lever 80 rocked out of the path of the pawl 78 so that the clutch remains engaged for a number of cycles or as long as the key is held depressed.

In accordance with the invention means are provided to maintain the reversing gear engaged to cause registration as long as the plus or minus key is depressed and the clutch is engaged. For this purpose the clutch 70 is provided with a cam 108 (Fig. 7) attached to the driven side which has a depression 109 to receive a roller 110 on the lever 80 when the clutch is disengaged. Upon movement of the driven side of the clutch out of full cycle position the high part 111 of the cam 108, which is an arc about the axis of shaft 76 as a center, moves under the roller 110 to maintain the lever 80 rocked out during the cycle even though the plus or minus key is released by the operator. The lever 99 has a hook-like depending portion 112 (Fig. 8) adjacent the notch 106 against which the pin 107 bears to maintain the lever 99 in its rear position during the major part of the cycle and at least as long as the registration portion of the cycle so that the shaft 80 is maintained in its rocked position holding the lever 80 rocked rearwardly. Holding the lever 80 rearwardly locks the depressed plus or minus key down; for example, in Fig. 8 it will be noted that the pin 85 of the plus key 50 is at the bottom of the slot 87 and due to the inclination of the slot, the key is prevented from rising, pressure being applied to the pin by the side of the slot

as indicated by the arrow 113. Furthermore, the other key 51 is locked up by a portion 114 of the lever 89 being maintained under the pin 86 on the key 51. When the minus key 51 is depressed, the parts operate in a similar manner to lock the minus key down and prevent depression of the plus key.

Referring to Fig. 2 it will be recalled that the plus and minus keys cause rocking of the lever 54 which causes rocking of the shaft 34 to position the reversing gear. Therefore, as long as either key is held depressed, the reversing gear will be maintained in drive transmitting position. In this manner the reversing gear is locked in its adjusted position throughout the major portion of each cycle to insure complete registration of the value set in the keyboard, this cyclic locking being controlled by the cam 108 on the clutch.

When the lever 103 is adjusted to its down position (Fig. 9), the link 100 is moved rearwardly to rock the lever 99 counterclockwise and to lift the notch 106 off the pin 107. The rear end of the lever 99 has a cam face 115 which, in the down position of the control lever 103, is positioned opposite a ledge 116 secured to the frame plate 31 (see Fig. 3). Upon depression of either the plus or minus key, rearward movement of the lever 99 results in camming the rear end of lever 99 upwardly so that the rear end of the lever is supported on the ledge 116 as shown in Fig. 10.

Referring to Fig. 4 it will be recalled that a second lever 98 is pivoted at 97 on the lever 91. The forward end of this lever is urged downwardly by a spring 117. At the rear end of the lever a notch 118 (Fig. 9) is provided which engages the pin 107 on the clutch control lever 80 so that with the control lever 103 in its down position, depression of either the plus or minus key will result in moving the lever 98 rearwardly to cause rocking of the clutch control lever 80 to effect engagement of the clutch. In order to limit rotation of the clutch to a single cycle, means are provided to cause the notch 118 to be disengaged from the pin 107 after the clutch has been engaged. For this purpose the lever 98 has a cam face 119 which engages a stud 120 secured to a frame plate 121 (Fig. 3) so that upon rearward movement of the lever 98, as shown in Fig. 10, the rear end of the lever is cammed downwardly to release the lever 80. However, the cam 108 maintains the clutch control lever 80 rocked out during the cycle as explained before and the pin 107, as shown in Fig. 10, is maintained against the hook 112 on the lever 99 so that the reversing gear is maintained engaged during the cycle to insure registration. When the clutch approaches its full cycle position (Fig. 11) at the conclusion of one cycle, the lever 80 is free to rock counterclockwise and disengage the clutch thereby limiting the operation to a single cycle even though the key is held down.

I claim:

1. In a calculating machine having an accumulator, actuating means therefor, transmission mechanism to control actuation of said accumulator by said actuating means, means tending to adjust said transmission mechanism to neutral, means movable to adjust said transmission mechanism to cause registration in said accumulator upon operation of said actuating means, drive means for said actuating means including a cyclic

clutch and a control therefor normally occupying a clutch disengaging position and movable to a clutch engaging position, an operation key, means actuated by depression of said key for moving said movable means to adjust said transmission mechanism, means actuated by depression of said key and including two members for moving said clutch control to clutch engaging position, means for disengaging one of said members from said clutch control after said clutch control has been moved to clutch engaging position, said other member being adjustable to two positions, said other member being capable of moving said clutch control to clutch engaging position in one of said positions but being incapable of moving said clutch control in the other position, means controlled by said drive means to retain said clutch control in clutch engaging position when said drive means is out of full cycle position, cooperating means on said clutch control and said other member to enable said clutch control to retain said other member in actuated position in both its adjusted positions, and cooperating means on said key and said clutch control moving means to enable said clutch control moving means to retain said key in depressed position whereby in both single cycle and plural cycle operations said transmission mechanism is retained in registering adjustment as long as said clutch remains engaged.

2. In a calculating machine having an accumulator, actuating means therefor, a reversible transmission mechanism to control actuation of said accumulator by said actuating means, means tending to adjust said transmission mechanism to neutral, a control for said transmission mechanism adjustable to cause additive or subtractive registration in said accumulator upon operation of said actuating means, drive means for said actuating means including a cyclic clutch and a control lever therefor normally occupying a clutch disengaging position and movable to a clutch engaging position, plus and minus keys, means actuated by said keys to selectively adjust said transmission control, a lever common to both keys having pin and slot connections with each, said connections being arranged so that depression of either key will rock said lever and so that as long as said lever remains rocked the depressed key is held down thereby, means actuated by said lever for moving said clutch control lever to clutch engaging position including two members adapted to engage said control lever, means for automatically disengaging one of said members from said clutch control lever after said clutch control lever has been moved to clutch engaging position, the other of said members being adjustable to two positions, said other member being capable of moving said clutch control lever in one position and being incapable of moving said lever in the other position, means controlled by said drive means to retain said control lever in clutch engaging position when said drive means is out of full cycle position, a portion of said other member being engaged by said clutch control lever whenever said clutch control lever is in clutch engaging position whereby a depressed key is held down as long as the clutch control lever is in clutch engaging position.

ANTHONY B. MACHADO.
